UNITED STATES PATENT OFFICE.

JOHN LLOYD WRIGHT, OF CHICAGO, ILLINOIS.

GAME AND GAME APPARATUS.

1,268,659.

Specification of Letters Patent.

Patented June 4, 1918.

Application filed September 25, 1916. Serial No. 121,972.

To all whom it may concern:

Be it known that I, JOHN LLOYD WRIGHT, a citizen of the United States, and a resident of Chicago, in the county of Cook and State 5 of Illinois, have invented certain new and useful Improvements in Games and Game Apparatus, of which the following is a specification.

My invention relates to improved game 10 and game apparatus, the game being known as "Hobbyhorse checkers."

The elements for playing the game are a checker-board and playing pieces consisting of horses and men, these pieces being of 15 unique construction and the men being adapted to be mounted on or dismounted from the horses, all these combinations forming part of the game when played.

On the accompanying drawing

20 Figure 1 diagrammatically represents in plan view an ordinary checker-board with the sixty-four squares.

Fig. 2 is a perspective elevational view of one of the men, and

25 Fig. 3 is a perspective view of one of the horses with a man mounted thereon.

5 represents a checker-board which may be of ordinary construction with the sixty-four checker squares 6. The checker squares 30 may be colored as desired, as shown one-half are red and the alternate squares are white.

The man shown is turned up of a single piece of wood and comprises the cylindrical body 7, the lower section being of reduced 35 diameter vertically cut or slotted as indicated at 8 to leave the semi-cylindrical legs 9 and 10 with the semi-cylindrical flanges 11 and 12 at their lower ends forming supporting bases or feet. Above the body part 40 is the reduced cylindrical section 13 representing the neck and head, and the upper end of this section is colored to represent the cap 14.

The horse is of unique design constructed 45 entirely of wood. A rectangular flat piece of wood is cut and notched to form the body 15, the neck 16, head 17, ears 18 and tail 19. The front legs 20 and 21 of the horse are 50 of wood and are secured at angles with each other, under the neck 16 and against the shoulder 22. The legs may be separate pieces, or part of a V shaped piece of wood. The rear legs 23 and 24 are secured to the body 15 in the notch 25. The slot 8 of the 55 man is of a width to easily receive the body

of the horse as clearly shown in Fig. 3, and pins 26 and 27 may be provided at the top of the horse body for centering and holding the man thereon and also to represent a saddle.

The game is intended to be played by two people and the pieces are moved back and forth much in the same manner as in the game of checkers, four horses and twelve men being used by each player, the men on one side having caps of different color from those on the other side, Fig. 2 showing a white cap and Fig. 3 showing a red cap. The horses and men may also be differently colored. To win, one player must eliminate 70 from the board by jumping all of the men from the other side. A man can move, jump, mount and dismount. A hobbyhorse has no privilege, while a horse-man, that is a hobbyhorse with a man thereon, can move 75 and jump. A man can move forward only, while a horse-man can move forward or backward. A man can jump another man only, while a horse-man can jump any piece on the board. A man can mount by jumping onto a hobbyhorse from an adjoining checker space, and a man can dismount by jumping over a horse-man whereupon the man on the horse is eliminated from the board, leaving the horse free.

The game can also involve other moves and is very interesting and fascinating and is very desirable for children as it is much more interesting than the ordinary game of checkers and not as difficult to play as chess.

I do not, of course, desire to be limited to the exact construction of the pieces, as changes may be made without departing from the spirit of the invention.

I claim as follows:

1. A player piece for checker-boards consisting of a hobbyhorse and a man, said horse consisting of a flat rectangular piece of wood notched transversely to represent the body, neck, head and tail parts and wood pieces secured at their upper ends to the ends of the body and extending therefrom at angles with each other to form legs, said man being turned from a single piece of wood and slotted at its lower end to be 100 placed astride the horse body.

2. Player pieces for checker boards comprising a hobbyhorse and a man, said horse consisting of a flat piece notched to represent a body and head and having legs se- 110

cured thereto, said man being a piece of material of general cylindrical shape having its lower end slotted longitudinally to form legs and having flanges at the lower ends of 5 the legs, said flanges enabling the man to stand alone and said slot enabling the man to be placed astride the horse whereby said

man and horse can be used either separately or as a single unit.

In witness whereof I hereunto subscribe 10 my name this 19th day of September, A. D. 1916.

JOHN LLOYD WRIGHT.
